DECANTER

Walter T. Heintze, New Canaan, Conn., assignor to Richardson-Merrell Inc., New York, N.Y., a corporation of Delaware

Filed Jan. 15, 1964, Ser. No. 78,202

Term of patent 14 years

(Cl. D58—6)

FIG. 1

FIG. 2

The dominant features of my design reside in the portions shown in full lines.

I claim:

The ornamental design for a decanter, substantially as shown and described.
